UNITED STATES PATENT OFFICE.

THOMAS A. COLLISON, OF LEBANON, PENNSYLVANIA.

RAILWAY-CAR BOLSTER.

No. 918,736.

Specification of Letters Patent.

Patented April 20, 1909.

Application filed October 26, 1906. Serial No. 340,660.

To all whom it may concern:

Be it known that I, THOMAS A. COLLISON, a resident of Lebanon, in the county of Lebanon and State of Pennsylvania, have invented a new and useful Improvement in Railway-Car Bolsters; and I do hereby declare the following to be a full, clear, and exact description thereof.

This invention relates to bolsters for railway cars, either truck bolsters or body bolsters.

The object of the invention is to provide an all wrought metal bolster formed in a single piece, which is light yet strong, and which is cheap and easy to manufacture.

The invention consists, generally stated, in forming the bolster from a plate by pressing and bending to form top and bottom chord members and a connecting web or webs, as hereinafter described and claimed.

In the accompanying drawings, Figure 1 is a plan view of a bolster constructed according to my invention; Fig. 2 is in part a side view and in part a central longitudinal vertical section thereof; Fig. 3 is a longitudinal section at the end of the bolster on the line 3—3, Fig. 1; Fig. 4 is a vertical cross section on the line 4—4, Fig. 1; Fig. 5 is a similar view on the line 5—5, Fig. 1; Fig. 6 is a plan view showing the invention applied to a body bolster; Fig. 7 is in part a side view and in part a central vertical section of the same; and Fig. 8 is a cross section on the line 8—8, Fig. 6.

My bolster is formed from a single plate pressed and bent to shape to provide suitable top and bottom chord members and a connecting web or strut, thus dispensing with all riveting, punching or other operations for connecting the members, making a bolster which is cheap, light and strong.

Figs. 1 to 5 show the invention adapted for a truck bolster. This bolster has a top plate 1 which at its edges is bent back upon itself, as at 2, and carried inwardly toward the neutral axis of the bolster to form flanges 3, and bottom members of the plate then being bent at right angles and extending downwardly forming vertical web members 4 which may be directly in contact with each other but which preferably are spaced apart, as shown, so as to give greater equilibrium to the bolster and make it more stable against rolling movements. Both web members of the bolster have their lower edges turned outwardly to form flanges 5 which form the bot-

tom chord of the bolster. This bolster is preferably made of greater depth at its middle than at its ends, as shown in Fig. 2. The lower edge may be curved, as shown in said figure, or may be a straight inclined line from the center toward the ends as shown in Fig. 7. The end portions of the bolster preferably are provided with horizontal lower edges so as to give a good bearing for the spring caps. The bolster is shown provided with a center brace 7 formed as a casting inserted between the web members and secured thereto by rivets 8 passing through alining openings in the web members and casting. This casting is provided with a central opening 8^a located beneath an opening 9 in the top plate for receiving the king pin. At its bottom it is preferably provided with the outwardly projecting wings 10 which are riveted to the bottom flanges 5 of the bolster. The ends of the bolster are also preferably provided with braces 12 in the form of castings inserted between the web members of the bolster and secured by means of rivets 13. Column guides 14 shown as castings, are secured to the outer faces of the webs by means of the rivets 13. Bearing plates 15 are also provided at the ends to rest on the truck springs, which plates may either be integral parts of the castings 12 or separate plates riveted to the bottom flanges of the bolster. A center bearing plate 17 and side bearings 18 are riveted to the top plate 1.

This bolster can readily be adapted as a body bolster, this being shown in Figs. 6, 7 and 8. This modification shows the lower edge of the bolster formed on inclined straight instead of curved lines as in Fig. 2, but obviously the forms are interchangeable in this respect. When used as a body bolster, the center bearing plate 19 and side bearings 20 are secured to the lower edge of the bolster, such as providing the same with web portions 20^a projecting up in between the web members of the bolster and secured to the latter by rivets 21 and also having flanges 22 which are riveted to the bottom flanges of the bolster. To the end of this bolster may be secured a casting 24 to serve as a support for the side stringers of the car body.

The design shown is very elastic, as it is possible, by making the plate of greater or less width, to very materially vary the bolster so as to take care of all conditions of

- use. For instance, if greater strength is needed, the plate may be left slightly wider, thus forming very wide bottom flanges 5 which add materially to the strength of the bolster to resist both vertical loads and end shocks. By slightly tapering the plate, these bottom flanges 5 may be made wider at the central portion of the bolster, as shown at 25, Fig. 6.
- 10 The bolster body is composed of only a single piece which can be bent to shape by suitable dies, either hot or cold. This does away with all the punching and riveting necessary in making a built up bolster. The usual appurtenances, such as center and end braces, center plate and side bearings can be easily connected to the bolster. The latter in cross section is of general I shape having the top or compression chord formed by the flanges 3 which are of double thickness of metal, the bottom or tension chord formed by the flanges 5, and the web being double and spaced apart so as to get somewhat the effect of a box girder. The bolster is very strong for the quantity of metal used and, as above stated, the design is such that by merely varying the width or shape of the plate the bolster can be varied to meet various conditions of use.
- 15 While in the drawings I have shown only one general cross section, I wish it understood that the invention comprehends the use of a single plate bent to form cross sections which may be materially different from that shown and I wish it understood, therefore, that no limitations are to be imposed upon the terms of the claims hereinafter made, either by the specific illustration or specific description.
- 20 30 What I claim is:
1. A bolster comprising a single plate and being hollow and provided with top and bottom laterally projecting portions, and side and center bearings secured to one of said laterally projecting portions.
  2. A bolster comprising a single plate provided with laterally projecting top and bottom chords and a vertical connecting web, and column guides secured to said webs.
  3. A bolster comprising a single pressed plate and being of general I-shape in cross section, side and center bearings secured to one of the flanged edges of said plate, and column guides secured to the web thereof.
  4. A bolster composed of pressed plate and having top and bottom flanges and a connecting web, one pair of said flanges being of double thickness of plate, and side and center bearings secured to one of the pairs of flanges of said bolster.
  5. A bolster composed of pressed plate having top and bottom flanges and a connecting web, the top flanges being of double thickness of plate, and side and center bearings secured to one of said flanges.
- 25 35 40 45 50 55 60
- thickness of plate, and side and center bearings secured to one pair of said flanges.
6. A bolster comprising a single pressed plate having laterally projecting top and bottom chords and a connecting web, said web being of double thickness of plate, and column guides secured to said web.
7. A bolster formed of a single pressed plate having laterally projecting top and bottom chords and a connecting web, the latter being of two thicknesses of plate spaced apart.
8. A pressed steel bolster having top and bottom chords and a connecting web, said web being formed of two thicknesses of plate spaced apart.
9. A pressed steel bolster having top and bottom flanges and connecting web, the top flanges and the web being a double thickness of plate, said web plates being spaced apart.
10. A bolster formed of a pressed plate and having a top plate bent back on itself to form flanges, then bent downwardly to form webs spaced apart and then outwardly to form a bottom chord.
11. A bolster formed of a single pressed plate of hollow form with top and bottom laterally projecting portions and of varying depth.
12. A bolster formed of a single pressed plate having laterally projecting top and bottom chords and a connecting web, the latter being of varying depth.
13. A bolster formed of a single pressed plate of general I form, having top and bottom flanges and a connecting web, the latter being of varying depth.
14. A bolster of general I shape in cross section comprising a single pressed plate construction having a double web member spaced apart.
15. A bolster of general I shape in cross section composed of a single pressed plate having a double web member, and braces secured between said web members.
16. A bolster comprising a top chord, a bottom chord, and a connecting web, formed of pressed plate metal and having one of the chord members and the web member of double thickness of plate.
17. A bolster formed of a single piece of metal pressed into I-beam form and cross section, such bolster at the center being relatively wider than at the ends, and a center plate and column guides secured to said bolster.
- In testimony whereof, I the said THOMAS A. COLLISION have hereunto set my hand.
- THOMAS A. COLLISION.
